UNITED STATES PATENT OFFICE

132,706

DESIGN FOR A JAR OR SIMILAR RECEPTACLE

Henry Worth and Michael D. Goldsmith,
New York, N. Y.

Application March 26, 1942, Serial No. 106,336

Term of patent 14 years

To all whom it may concern:

Be it known that we, Henry Worth and Michael D. Goldsmith, citizens of the United States and residents of the city, county, and State of New York, have invented a new, original, and ornamental Design for a Jar or Similar Receptacle, of which the following is a specification, reference being had to the accompanying drawing, forming a part thereof, in which—

Fig. 1 is a side elevational view of a jar or

similar receptacle embodying our new design; Fig. 2 is a side elevational view of the same taken at right angles to that of Fig. 1 and Fig. 3 is a plan view of the same.

We claim:

The ornamental design for a jar or similar receptacle, substantially as shown.

HENRY WORTH.
MICHAEL D. GOLDSMITH.
